[57] **CLAIM**

The ornamental design for a tire, substantially as shown
and described.

DESCRIPTION

The FIGURE is a perspective view of a tire showing
our new design, it being understood that the tread de-
sign is repeated throughout the circumference of the
tire as shown schematically by solid lines, the opposite
side being substantially the same as that shown.

U.S. Patent

Jan. 22, 1980

Des. 254,000

Dedication

Des. 254,000.—*Michael A. Kolowski*, Tallmadge; *Daniel J. Lindner*, North Canton, both of Ohio; *Henry T. Kwee*, Stow; *Charles W. Roberts*, Akron, Ohio; *Harold D. Fetty*, Birmingham, Mich. TIRE. Patent dated Jan. 22, 1980. Dedication filed May 12, 1989, by the assignee, The Goodyear Tire & Rubber Company.

Hereby dedicates to the Public the entire term of said patent.
